UNITED STATES PATENT OFFICE.

ARTHUR PRATT, OF DUKINFIELD, ENGLAND.

EXHAUST-MUFFLER.

No. 879,583.

Specification of Letters Patent.

Patented Feb. 18, 1908.

Application filed May 16, 1906. Serial No. 317,093.

To all whom it may concern:

Be it known that I, ARTHUR PRATT, a subject of the King of Great Britain and Ireland, and residing at The Mount, Crescent Road, 5 Dukinfield, in the county of Chester, England, have invented new and useful Improvements in Exhaust-Mufflers, of which the following is a specification.

The principal object of this invention is to 10 allow the exhaust gas on leaving the engine under pressure, to undergo a considerable amount of expansion before it leaves the "silencer" whereby the sudden impact of the said exhaust gas against the atmospheric 15 pressure is greatly reduced, and hence the "silencing" is much more effective than hitherto.

The exact nature of my invention and the manner in which the same is to be performed 20 or carried into practical effect will be readily understood on reference to the sheets of drawings annexed and the following explanation thereof.

Figure 1 on Sheet 1 of the drawings is a 25 longitudinal section, and Fig. 2 on Sheet 2, an end view of the improved "exhaust silencer" constructed according to my invention, and Figs. 3 and 4 are similar views of a modification of the same hereinafter more 30 particularly referred to.

According to and for the purpose of my invention the body of the casing of the "silencer" is composed of two sheet iron cylinders *a* and *b*, one made to fit inside the other, 35 with a sheet of asbestos, or other suitable non-conducting material or compound between them, which also serves to muffle the sound of the exhaust gas from the engine. These cylinders *a* and *b* are fitted together with cast 40 metal ends *c* with holes in the center, and through these holes at each end passes a central tube *d* and *d'*. These tubes are screwed externally at each end and provided with nuts *e*, to fix all firmly together.

45 The tubes *d* and *d'* are perforated with a number of small holes *f*, *f'* and *f''* and are fitted with two iron disks *g* and *g'* to form stops, one at the end of the first group of perforations *f*, and another at the end of the 50 third group *f''*. Each tube also contains an internal spiral or worm *h*, *h'* one at the inlet *a* and the other at the outlet. These spirals fit closely into the tubes so that the exhaust gas passing through the tubes is compelled to 55 take a spiral course.

Fitting closely on the center tube *d'* but so

as to slide easily backwards and forwards thereon, are two disks or stops *h''* which are perforated with a few small holes, and are rather smaller in diameter than the inside 60 cylinder *b*. These disks are attached to brass bosses or bearings *i* which slide on the tube *d'*, and on each side of the said bosses is a spiral spring *j*, *j'*, *j''* fitting round the central tube *d'*.

The operation of this improved "silencer" 65 is as follows:—The exhaust gas on leaving the engine under considerable pressure enters the tube *d* at the inlet opening and passes round the worm or spiral *h* and outwards 70 through the holes *f* into the outer chamber forcing the disks or stops *h''* forward against the action of the springs *j*, *j'*, *j''* thus causing the chamber to enlarge or expand. The reaction of the springs will gradually force the 75 disks *h''* back again as the gas passes through the small perforations above mentioned. The gas then passes through the holes *f'* into the central tube *d'* round the spiral *h'* and out of the holes *f''* into the atmosphere.

The arrows on the drawing show the direction which the gas takes. The action of this improved "silencer" causes the exhaust to extend over a longer period than heretofore and entirely does away with the rapid puffing sound, causing the exhaust to be extremely silent.

As a modification I sometimes propose to make the casing of the improved "silencer" 80 of a rectangular form in cross-section as shown at Figs. 3 and 4 of the drawings, and instead of the sliding disks or stops *h''*, at or near the center of the casing I have a sheet metal flap or door *k* which is hinged at the top and has a few small holes made through 85 it. The interior of the casing is provided with a curve or sweep *l* having the same radius as the flap or door *k*, so that the lower end almost touches it, a small space only being left for clearance. The inlet tube *d* 90 entering the chamber at one end, and the outlet tube *d'* leaving it at the other. The said tubes are perforated and fitted with internal worms or spirals *h* and *h'* as in the previously described arrangement. When the 95 exhaust gas from the engine enters the first chamber of the casing through the perforations *f* it moves the door or flap *k* upwards, thus causing the chamber to enlarge or expand. The gas then passes more slowly 100 through the small holes in the flap or door, and its own weight brings the latter back

again. This action and re-action as in the former case causes the exhaust to extend over a longer period, and thus does away with the puffing noise, which usually accompanies the exhaust in connection with petrol, gas, and oil engines as hitherto constructed.

5 I claim as my invention:—

1. An exhaust muffler comprising an expansion chamber, inlet and exhaust ports 10 opening into the same and a flexibly mounted baffle between said ports, adapted to be actuated by and at all times to permit the passage of the exhaust vapors to the exhaust port.

15 2. An exhaust muffler comprising an expansion chamber, perforated inlet and exhaust tubes opening into the same and a flexibly mounted member adapted to be actuated by the exhaust vapors interposed in 20 said chamber between the inlet and exhaust ports.

25 3. An exhaust muffler comprising an expansion chamber, inlet and exhaust tubes opening into the same, an internal worm for each of said tubes, and a flexibly mounted

member adapted to be actuated by the exhaust vapors interposed in said chamber between the inlet and exhaust ports.

4. An exhaust muffler comprising an expansion chamber, perforated inlet and exhaust tubes opening into the same, a perforated flexibly mounted baffle interposed in 30 said chamber between the inlet and exhaust ports and adapted to be actuated by the exhaust vapors.

5. An exhaust muffler comprising an expansion chamber, perforated inlet and exhaust tubes opening into the same and provided respectively with an internal worm, a 40 perforated flexibly-mounted baffle interposed in said chamber between the inlet and exhaust ports and adapted to be actuated by the exhaust vapors.

In testimony whereof I have signed my name to this specification, in the presence of 45 two subscribing witnesses.

ARTHUR PRATT.
